PENNSYLVANIA.

FLIGHT ATTACHMENT FOR CONVEYER-CHAINS.

1,335,697.

Specification of Letters Patent. Patented Mar. 30, 1920.

Original application filed December 22, 1917, Serial No. 208,466. Divided and this application filed March 8, 1918, Serial No. 221,303. Renewed February 6, 1920. Serial No. 356,420.

To all whom it may concern:

Be it known that we, RALPH W. PATTEN, DAVID G. DAVIS, and EDWARD L. BURLEIGH, citizens of the United States, residing at 5 Scranton, in the county of Lackawanna and State of Pennsylvania, have invented certain new and useful Improvements in Flight Attachments for Conveyer-Chains; and we do hereby declare the following to be a full, 10 clear, and exact description of the invention, such as will enable others skilled in the art to which it appertains to make and use the same.

This invention relates to chain-conveyers, 15 and particularly to flight and link structures thereof.

In the making of repairs and replacement of parts and the adjustment of the same, much valuable time is lost because of the 20 necessity of entirely removing a link or links from a chain therefrom, and again because it is necessary to slacken up the chain-belt by considerably running up the foot or tightening wheel to permit the removal of 25 a link.

It is, therefore, among the more important objects of this invention to provide a chain and flight structure whereby the time taken for making various adjustments or replacement of parts is materially shortened; the necessity of entirely removing a link with 30 a flight is entirely eliminated, and the desired security and rigidity of connection is accomplished.

With these, and other objects in view as will be readily manifest to those skilled in the art, the invention consists of the construction, combination, details, and the arrangement of parts as more fully set forth 40 in the following specification wherein one embodiment of the invention is described as shown in the accompanying drawing, in which—

Figure 1 is a bottom plan view of two 45 links and a flight.

Fig. 2 is a section on line 2—2 of Fig. 1.

Fig. 3 is a side elevation of Fig. 1.

Fig. 4 is a detail front perspective view of the chair.

The chain is made of a plurality of links shown here as comprising a center, female block link 2 of oblong elevation with rounded ends 3, and sides indented at 5, the shoulders 6 being square, and as outside

complementary paired link sections 7. The 55 sections 7 are duplicate, and, therefore, are interchangeable, and each is of such construction that it may be reversed end for end if desired.

Each of the center or block links 2 and 60 the side link sections 7 are of hollow form; that is, each is provided with a slot or slots 8 of suitable length and diameter to receive a cross-pin 10, having a diameter approximating the width of the slots 8, this pin 65 having at each end a T-head 11, which are parallel to each other and extend in a common plane diametrically across the axis of the pin 10, the length of the heads 11 being here shown as substantially equal to the 70 width of the link components of the chain, the ends of the outside or male link section 7 being provided with respective seats 12 of a width substantially equal to the width of the T-heads 11 of the pivot pins, and into 75 which the projecting portion of the heads are adapted to snugly seat when the rounded ends of each of the links 2 and 7 are brought into concentric relation as by the pulling of the central or female link 2 to one end 80 of the outer pairs of link sections 7, so that the cylindrical body of the pivot pin 10 bears respectively in the rounded end portions of the slots 8 in the chain.

It is an important object of the present 85 invention to provide for the ready and rapid removal or dismounting of a conveyer flight from a conveyer chain, and to that end our invention consists in the provision of a unitary or integral chair, generally indicated at 15, and comprising an upright flange or seat 16, from which rearwardly projects a base plate 17 adapted to rest upon the top of one of the center or female block links and having downwardly projecting 90 parallel spaced ears 18 of a depth below the base 17 substantially equal to the thickness of a center link, and of a length substantially equal to the length of the indented recesses or seats 4 on the sides of the block link so 100 as to snugly fit against the shoulders 5 thereof, so that these two parts when assembled are rigid and secure. The inside surfaces of the ears 18 are spaced apart obviously a distance substantially equal to the 105 width of the central portion of the block 2 between the parallel longitudinal surfaces of the seats 4—4, and if desired, bracing

webs 19 may be provided to reinforce the ears 18 below the base 17. This latter may also be provided with a bracing web 20, connecting the seat or plate 16 and the base 17.

5 To secure the chair 15 to its center link 2, the ears 18 are shown as provided alined polygonal apertures, having a diameter substantially equal the width of the slot 8 in the center block or link, and through this 10 slot and these apertures there may be passed a polygonal bolt 21, having a head 22 on one end and a threaded portion at its opposite end to receive a nut 23 passed over the projecting threaded portion of the locking bolt 15 21. The polygonal body of the bolt fitting the slot of the center block 2 prevents the bolt from rotating, and it also snugly fits the apertures in the depending ears.

This chair is provided at its lower portion, 20 and projecting in front of the upright seat 16, with a rectangular shoulder 25, and in front of this there is spaced a hook portion 26, between which and the face of the shoulder 25 is provided a space to receive the 25 lower edge of a washer plate 27, perforated at 28 to receive fastening bolts 29, which are adapted to pass through a flight plate 30, having a notch at 31 to pass over the shoulder 25, which latter locks the flight plate 30 30 against shifting movement when it is clamped between the washer plate 27 and the upstanding seat 16 of the chair by the bolts 29. The lower edge of the flight plate 35 rests upon a forwardly projecting shoulder 32 extending along the front edge of the base of the chair, and carries at its transversely projecting lower corners a set of removable and duplicate wearing shoes 33 which are detachably secured to the plate 40 30 by bolts 34.

From the above it will be seen that we have provided a unitary chair which is adapted to be securely and rigidly mounted upon a central link of a chain conveyer, and 45 is readily detachable by the simple removal of the bolt or bolts fastening it to the center

block link, and it will be seen that it is not necessary to remove a link or links off the chain in order to remove the flight chair from the chain, nor is it necessary to remove 50 the chair from the link when it is desired to insert a new flight plate 30. By the provision of the removable and renewable washer plates 27, the durability of the flight plate 30 is greatly increased as the wear of the bolt 55 heads upon this plate is entirely removed and taken by the washer plate 27.

This application is a division of our application filed December 22, 1917, Serial No. 208,466.

60 What is claimed is:

1. A chair for conveyer chains, consisting of a flat base member having an upstanding seat flange with a central locking shoulder, and a removable flight plate to bear 65 against said seat and notched to interlock with said shoulder.

2. A unitary chair for a conveyer flight, having an upstanding seat flange with a ledge along the edge and a retaining hook 70 in front of said ledge, a flight plate adapted to be applied to said seat and bear on said ledge, and a washer disposed between said hook and flight plate and on which the wear of fastening means is taken.

75 3. An attachment, for conveyer chains, comprising a chair having a flat base portion to be transversely laid flat upon the top of a link and having dependent perforated lugs to embrace the sides of the link, a 80 perpendicular seat-flange on the top of the base set back from the front edge thereof to form a ledge, a lug at the central portion of the flange and ledge, and a forwardly extending hook to underhang a washer, the 85 flange perforated to receive bolts for attaching a plate thereto.

In testimony whereof we affix our signatures.

RALPH W. PATTEN.

DAVID G. DAVIS.

EDWARD L. BURLEIGH.
